UNITED STATES PATENT OFFICE.

EDWARD A. LARSON, OF CHICAGO, ILLINOIS, ASSIGNOR TO STEWART-WARNER SPEEDOMETER CORPORATION, OF CHICAGO, ILLINOIS, A CORPORATION OF ILLINOIS.

AUTOMOBILE-RADIATOR THERMOMETER.

1,177,712.

Specification of Letters Patent.

Patented Apr. 4, 1916.

Application filed July 6, 1914. Serial No. 849,073.

To all whom it may concern:

Be it known that I, EDWARD A. LARSON, a citizen of the United States, residing at Chicago, in the county of Cook and State of Illinois, have invented new and useful Improvements in Automobile-Radiator Thermometers, of which the following is a specification, reference being had to the accompanying drawings, forming a part thereof.

10 This invention relates to improvements in a temperature indicating device for automobile radiators designed to insure that the reading of such indicator shall correspond as closely as possible with the actual temperature of the water in the radiator.

15 The invention consists in the features and elements described and shown in the drawings, as indicated by the claims.

In the drawings:—Figure 1 is an elevation partly in section, showing a portion of an automobile radiator having a temperature indicator mounted therein, embodying the improvement which is the subject of this invention. Fig. 2 is an enlarged detail view, 25 principally in section.

The temperature indicator used for purposes of illustration is a metallic thermometer comprising a bi-metallic bar or heat-responsive element, 1, whose curvature is varied in a well understood manner by variations of temperature and which operates upon a push-pin, 2, to actuate mechanism not shown in detail but including an indicating needle, 3, which traverses a scale, 4, graduated in terms of temperature. For convenience and simplicity, it is considered desirable to mount this device in the usual filler cap, 5, which constitutes the closure of the neck, 6, ordinarily provided on the 30 radiator. This positions the device where it can be easily read from the driver's seat, and in no way interferes with the water piping connections between the radiator and the engine. By reason of the wide variation in 35 design of the filler neck, 6, however, it is found that if the frame member, 7, carrying the heat-responsive element, 1, is made of uniform length, it will project into the radiator far enough in some cars to reach the 40 cooling water therein, while in other cars, by reason of the greater length of the neck, 6, it will remain above the water level in the air space, so that the heat-responsive element, 1, is not subjected directly to the temperature of the water itself. Ordinarily

the water enters from the engine near the top of the radiator by a pipe indicated by the dotted circle, 8, but even so, the temperature of the air space above this hottest water bears no uniform relation to the temperature 60 of the water itself. To bring this hottest water closer to the heat-responsive element, 1, said element is surrounded with an upwardly-open and flaring cup, 9, preferably secured to the frame member, 7, as by a 65 screw, 10. In actual road use of the vehicle the water in the radiator will be splashed up into the neck, 6, and caught in the cup, 9, by which it will be held and permitted to influence the heat-responsive element, 1. A 70 leak port, 9a, is provided in the bottom of the cup to insure a constantly changing supply of water which shall have at all times practically the same temperature as the water in the upper portion of the radiator, 75 which is the hottest water and which therefore most accurately registers the condition of the engine as to temperature. Under some conditions it is found desirable to protect the heat-responsive element, 1, from 80 actual contact with the water, especially where such water is rather impure and would tend to set up electrolytic action between the two metals of the element, 1; in such instances the element, 1, may be provided 85 with an inclosing metallic jacket, 11, which will not materially interfere with conduction of heat from the water in the cup, 9.

I claim:—

1. A device for indicating the temperature 90 of the cooling water of an internal combustion engine, comprising, in combination with the cooling water system, a support adapted to be secured at an aperture leading thereto; a thermometer mounted on said support with its heat-responsive element inside and its temperature-indicating element outside the circulator system; an upwardly open water receptacle and means for supporting it within the circulator system, the 95 heat-responsive element of the thermometer being intruded into said receptacle, whereby it is exposed to the cooling water entering said receptacle from the circulator system, said receptacle having a leak port for the 100 slow escape of water therefrom at the lower part.

2. A device for indicating the temperature 105 of the cooling water of an internal combustion engine, comprising, in combination

with a radiator, a thermometer adapted to be mounted upon the radiator cap with its heat-responsive member protruding into the radiator through the filling mouth thereof; 5 a heat-conducting support for said heat-responsive member; a heat-conducting jacket attached to said support which incloses said heat-responsive member out of direct contact with the air which may be in the radiator above the water, and a cup into which said inclosing jacket extends which is opened upwardly within the radiator for reception

of water from the radiator to surround said inclosing jacket, said cup having a leak-port at the lower part for slow waste of 15 water from the cup.

In testimony whereof, I have hereunto set my hand at Chicago, Illinois, this 3rd day of July, 1914.

EDWARD A. LARSON.
